UNITED STATES PATENT OFFICE.

FRANK L. RICKER, OF PORTLAND, MAINE, ASSIGNOR TO AUSTRAL WINDOW COMPANY,
OF NEW YORK, N. Y., A CORPORATION OF MAINE.

WINDOW-SCREEN.

1,201,102.

Specification of Letters Patent. Patented Oct. 10, 1916.

Application filed October 24, 1913, Serial No. 796,988. Renewed September 9, 1916. Serial No. 119,279.

To all whom it may concern:

Be it known that I, FRANK L. RICKER, of Portland, in the county of Cumberland and State of Maine, have invented certain new and useful Improvements in Window-Screens, of which the following is a specification.

My invention relates to window screens and particularly to screens adapted to be used on the so-called "Austral" or balance sash windows. These windows are illustrated in United States Letters Patent No. 821,510 issued May 22, 1906, and they consist of an upper and lower sash with the usual meeting rails, the lower portion of the upper sash and the upper portion of the lower sash being pivoted at a point a short distance from their ends to the ends of a pair of centrally pivoted balance levers which are in turn pivoted to the parting strip. The upper end of the upper sash and the lower end of the lower sash are pivoted in a vertical slot in the casing which allows them to move vertically. As a result of this construction the upper end of the lower sash may be swung inwardly and the lower end of the upper sash outwardly at the same time opening a space at the top and bottom of the window. These windows which have gone into extensive use have always been difficult to screen on account of their peculiar construction.

The object of my invention is to devise a screen which will perfectly close the window opening while allowing the sash to be freely opened and closed, which may be removed without leaving an opening between the meeting rails of the sash to be filled in by a removable filling piece and which may be freely opened while in place and without being removed. These objects I accomplish by means of the window screen hereinafter described and claimed.

My invention may best be understood by reference to the accompanying drawing in which is shown a window of the "Austral" type screened in accordance with my present invention.

In the drawing, Figure 1 is a central vertical section taken through the window, Fig. 2 is a partial elevation looking from the inside, Fig. 3 is a detail elevation showing the hub of the balance lever and its pivot block with the filling piece in section, Fig. 4 is a section taken on the line $\alpha\alpha$ of Fig. 3, Fig.

5 is a partial section on the line $\alpha\alpha$ of Fig. 1, Fig. 6 is a perspective view of one end of the filling piece, and Fig. 7 is a vertical section taken on the line $\alpha\alpha$ of Fig. 6. Fig. 8 is a modification in which the meeting rails 60 of the sashes close over the filling piece to make a closed joint.

Referring to Figs. 1-7 of the drawing, a represents the window casing, b the parting strip, c the upper sash, d the lower sash, 65 c' and d' the meeting rails of the two sashes. e is one of the balance levers pivoted by means of a pivot e' in a pivot block e^2 secured to the parting strip b .

The pivot block is provided with suitable 70 screw holes near its upper and lower ends and is secured to the parting strip by screws passing through these holes. The upper end of the upper sash and the lower end of the lower sash are connected with the casing by means of a vertical slot and pin connection to permit vertical movement of the sashes as indicated by dotted lines in Fig. 1. The lever has a hub or enlargement in the center and the ends are pivoted to the sash 75 by suitable connections. When screens are to be used the meeting rails are separated by an intervening space or opening.

The above are the parts of the "Austral" window as commonly constructed and need 80 no further description. For the purpose of screening this window, I provide an upper screen f which fits the casing above the sash d and rests against the inner face of the parting strip opposite the sash c and a lower 85 screen g which fits against the outer face of the parting strip opposite the sash d .

The screen f is pivoted by suitable means to the casing at or near its upper end. As here shown, I make use of pivoting screws 90 f' inserted in the sides of the casing and passing through clips and the screen g is pivoted in like manner preferably at its upper end by pivots g' . The lower ends of the screens are locked in place by dogs f^2 and 95 g^2 which engage slots in the casing in the usual manner.

The space between the adjacent ends of the screens is filled with a filling piece which makes a tight joint with the lower end of 100 the screen f and the upper end of the screen g when the latter are in closed position. As herein shown, this filling piece consists of an upper angular section h and a lower angular section i both being preferably 105 of 110

metal. The section h is bent to form a vertical flange h' and an inclined flange h^2 . The vertical flange h' extends vertically upward on one side of the opening between the meeting rails, projecting above the rail d' far enough to make a fly proof joint with the lower end of the screen f . The lower section i is the complement of the upper section, having a vertical flange i' which extends downwardly along the inner face of the rail c' and extending far enough below said rail to make a tight joint with the upper end of the screen g . The inclined flange i^2 fits against the under side of the inclined flange h^2 of the section h , the two abutting to form a tight joint which may include a gasket to make the joint impervious to rain, snow, dust or air. Means are provided whereby the filling piece may be secured to the parting strips at their ends, making use of the screw holes of the pivot blocks and bringing the vertical portions flush with the faces of the parting strips.

As shown, the ends of the inclined flanges i^2 and h^2 of the two sections h and i are cut away to fit closely around the hub of the balance lever e and the vertical flanges h' and i' are bent at right angles to form two fastening flanges h^3 and i^3 , these two flanges being vertically in line with each other. Each is provided with a screw hole which is in the exact position to fit one of the screw holes in the pivot block (see Figs. 3 and 4) and they are fastened in place by the same screws which hold the pivot block.

It will be seen that by releasing the dogs f^2 the screen f may be swung inwardly at the bottom, making an opening as large as desired. In the same manner the screen g may be opened by swinging the bottom outwardly. The filling piece having been once put in place need not be removed when the screens are taken out but may be left in place indefinitely.

In the winter the screens may be easily removed and double windows put in their place without disturbing the filling piece.

The screens and filling piece are here shown as being made of metal but they may be constructed if desired of wood and other changes may be made in the construction herein shown without departing from my invention as defined in the claims.

In Fig. 8 I have shown a modification in which the meeting rails of the sashes close over the filling piece to make a closed joint doing away with the recess between the rails. Referring to the Fig. 8 d^2 and c^2 are the meeting rails and h^4 and i^4 the upper and lower sections of the filling pieces. The upper section is bent to form a vertical lip 1 to connect with the screen f , thence it makes a horizontal bend 2 to about the center of the parting strip, thence downward vertically forming a vertical web 3 and then

horizontally, terminating in a flange 4. The lower section is formed in substantially the same way terminating in a flange 5 which is secured to the flange 4 by a bolt 6 or otherwise.

70

I claim:

1. The combination with a window of the character described, having an upper and a lower sash and parting strip, the meeting rails of said sash being separated by an intervening space, of an upper and lower screen, each fitting against the face of the parting strip opposite the corresponding sash and being pivoted by one end to the casing, a filling piece secured to the casing and positioned within said space, said filling piece making a joint with the adjacent ends of said screens.

75

2. The combination with a window of the character described, having an upper and a lower sash and parting strip, the meeting rails of said sash being separated by an intervening space, of an upper and lower screen, each fitting against the face of the parting strip opposite the corresponding sash and being pivoted by one end to the casing, a two part filling piece secured to the casing and positioned within said space, said filling piece making a joint with the adjacent ends of said screens.

80

3. The combination with a window of the character described, having an upper and a lower sash and parting strip, the meeting rails of said sash being separated by an intervening space, of an upper and lower screen, each fitting against the face of the parting strip opposite the corresponding sash and being pivoted by one end to the casing, a filling piece secured to the casing and positioned within said space or opening, said filling piece being composed of two similar sheet metal angle pieces having each a vertical flange making a joint with one of the adjacent ends of the screens, the other flanges of said angle pieces abutting to form a joint.

85

4. The combination with a window of the character described, having an upper and a lower sash, the meeting rails of which are separated by an intervening space, a balance lever pivoted to said sashes, a parting strip, a pivot block secured to said parting strip, said pivot block having screw holes therein, a filling piece for closing said space or opening, said filling piece having at its ends inwardly extending metal flanges provided with screw holes which register with the screw holes of said pivot block and fastening screws extending through said holes.

90

5. The combination with a window of the character described, having an upper and lower sash, the meeting rails of which are separated by an intervening space, a balance lever pivoted to said sashes, a parting strip, a pivot block secured to said parting

strip, said pivot block having screw holes therein, a two part filling piece for closing said space, said filling piece having at each end inwardly extending metal flanges provided with screw holes which register with the screw holes of said pivot block and fastening screws extending through said holes.

6. The combination with a window of the character described, having an upper and lower sash, the meeting rails of which are separated by an intervening space, a balance lever pivoted to said sashes, a parting strip, a pivot block secured to said parting strip, said pivot block having screw holes therein, a filling piece for closing said space, said filling piece being composed of two similar metal strips each bent to form two angular flanges, two of said flanges abutting within said space to form a joint, the ends of the other flanges being bent inwardly and provided with screw holes which register with the screw holes of said pivot block and fastening screws extending through said holes.

25 7. The combination with a window of the character described having an upper and lower sash, the meeting rails of which are separated by an intervening space, a bal-

ance lever to which said sashes are pivoted, a parting strip, a pivot block to which said lever is pivoted secured to said parting strip, said pivot block having screw holes therein, an upper screen pivoted by its upper end to the casing and fitting the same on the opposite side of the parting strip from the upper sash, a lower sash pivoted by its upper end to the casing and fitting the same on the opposite side of the parting strip from the upper sash, a two-part filling piece for closing said space, said filling piece being composed of two similar metal strips each bent to form two angular flanges, two of which abut within said space to form a joint, the two other flanges being vertical and making joints with the adjacent ends of the screens, the ends of the vertical flanges being turned in and provided with screw holes which register with the screw holes of said pivot block and fastening screws extending through said holes.

In testimony whereof I have affixed my signature, in presence of two witnesses.

FRANK L. RICKER.
